UNITED STATES PATENT OFFICE.

FREDERICK C. SCHOFIELD, OF LYNCHBURG, VIRGINIA, ASSIGNOR TO TOBACCO STEMMING MACHINE COMPANY, OF LYNCHBURG, VIRGINIA, A CORPORATION OF DELAWARE.

ART OF STEMMING TOBACCO.

Application filed December 10, 1921. Serial No. 521,320.

To all whom it may concern:

Be it known that I, FREDERICK C. SCHOFIELD, a citizen of the United States, and resident of Lynchburg, in the county of Campbell and State of Virginia, have invented certain new and useful Improvements in the Art of Stemming Tobacco, of which the following is a specification.

This invention relates to leaf stemming and more particularly to a method of and apparatus for stemming tobacco leaves; and has special reference to the provision of a leaf stemming method and apparatus of the type in which the web or lamina of the leaf is detached from the stem by stripping the leaf lamina from an intermediate point of the stem towards its opposite ends.

One of the common classes of machines used for stemming tobacco leaves comprises apparatus in which the principle is employed of seizing or gripping the stem of the tobacco leaf and stripping the web or lamina of the leaf from the stem as by drawing the gripped leaf through stemming or stripping elements. According to one type of machine employing this general principle, the leaf is seized or gripped at the butt end of the same and the leaf so gripped is fed through stemming elements which strip the lamina from the butt end towards the tip end of the leaf. Although in this type of machine the butt, being strong, tough and firm, may be securely gripped and the leaf efficiently fed through the stemming elements, it is well known that the detaching of the lamina from the stem is carried on with considerable difficulty, the stemming from butt to tip being with the grain of the leaf and in causing a crowding or bunching of the lamina about the stem being a fairly difficult operation. To overcome this disadvantage incident to stemming from butt to tip another type of machine has been devised in which the leaf is gripped or seized at the tip end and the stemming operation effected from the tip towards the butt. The stemming or stripping from tip towards butt involves a stripping against the leaf grain and such stripping may be effected with considerable ease and facility. However, in the latter type of machine, although the stripping step may be carried on to advantage, considerable difficulty has been encountered in properly gripping the tip end of the leaf

and feeding the leaf from the stemming elements by the gripped tip end, the thin relatively frail and infirm tip end of the leaf being liable to tearing and breaking when subjected to a moderate degree of pulling strain. This disadvantage has been so serious at times that in some forms of this latter type of machine special means have had to be devised for changing the gripping point of the stem from the tip towards the tougher part of the stem fibre as the leaf is progressively stripped therefrom. The type of machine, therefore, where the butt end of the leaf is seized and the leaf stripped from butt to tip is open to the disadvantage of difficult stripping or stemming; and the type where the tip end is gripped and the leaf stripped from the tip to butt is open to the equally serious disadvantage of insecure and imperfect gripping and feeding.

To eliminate the defects or disadvantages incident to such types of machines and to combine the desirable features thereof, a third type of machine has been devised in which the leaf stem is gripped at a point intermediate the ends thereof and the lamina stripped from such point towards the opposite ends of the leaf. The intermediate point of the stem consists of a relatively tough fibre and such part of the stem may be securely taken hold of and the leaf may be fed through stripping means with the stem so gripped without the liability of the stem breaking or tearing. Although part of the stemming, namely that from the gripped intermediate point towards the tip, is relatively difficult, the stemming from the gripped intermediate point towards the butt is carried on with ease. In this manner relatively facile stripping or stemming may be combined with efficient gripping and feeding operations.

Although this third type of stemming machine offers a way for generally eliminating the defects and for combining the advantages of the other machines in the class above referred to, prior machines of this last type have not been found to work with the consistency, ease and speed desired in the stemming art. Where the parts of the leaf on opposite sides of the intermediate point were stripped in successive steps, special gripping, feeding and stemming constructions had to be devised which were at

once cumbersome in structure and intricate in operation. Where the parts of the leaf were stripped in opposite direction simultaneously from the intermediate point, in addition to providing several sets of stemming rolls active on such parts with the resulting increase in complexity of the machine structure, special means for gripping the stem so as to take up for differential strains in opposite directions had to be incorporated in the machine because of the necessity to equalize stripping action in opposite directions, this being impossible of attainment without such means because of the fact that stripping in the direction towards the butt requires less resisting pull than stripping in the direction towards the stem, the draws in opposite direction being therefore unequal. Prior machines of this type, therefore, although logically correct in attacking the stemming problem on the broad principle of gripping at an intermediate point and stemming towards the opposite ends of the leaf, do not supply the best solution from the viewpoint of accomplishing the desired ends with relatively simple apparatus so that gripping, feeding and stemming can be carried on with the facility and speed attainable in this type of machine.

My present invention primarily contemplates the provision of an apparatus of the type last referred to in which the principle of gripping the stem at a point intermediate its ends and stripping the lamina or blade of the leaf from such point towards the opposite ends of the leaf is employed, my invention contemplating a novel method of and apparatus for gripping, feeding and stemming the blades, such method and apparatus not being subject to the defects found in prior machines of this type.

The principal objects of my invention may be said to include, besides the provision of a method of and apparatus for stemming tobacco leaves of the kind referred to, the provision of a method and apparatus in which the leaf is folded about the gripped point and the lamina detached from the resulting folds; the provision of a method and apparatus of this type in which the leaf is folded and fed in folded condition through a set of stemming elements, the folds of the leaf being simultaneously acted upon by the same set of stemming rolls, the apparatus required being relatively simple not only, but stemming being carried on with a tendency towards equalizing opposing pulls or draws on the stem and with secure stem gripping and feeding effected; the still further provision of a method and apparatus in which the lamina of the leaf is removed from the folds and from the gripped portion of the stem in a single operation; the still further provision of a novel

method and means for positioning the tobacco leaves and for feeding the grippers thereto and the general provision of simple, easily operated and controlled apparatus carrying on the various steps of the method. 70

To the accomplishment of the foregoing and such other objects as may hereinafter appear, my invention consists in the elements and their relation one to the other, as hereinafter particularly described and sought to be defined in the claims, reference being had to the accompanying drawings which show preferred embodiment of my invention and in which:

Figure 1 is a longitudinal sectional elevational view of my machine with parts broken away, 80

Figure 2 is a fragmentary rear elevational side view of the same.

Figures 3 to 5 are views showing the stemming of the tobacco leaves in successive stages, 85

Figures 6 to 8 are detail views of means for operating on the gripper bars to permit a full cleaning of the leaves in a single 90 operation, and

Figures 9 and 10 are views of modifications.

As hereinbefore referred to, a prime desideratum of my present invention comprehends the provision of a tobacco stemming construction in which the tobacco leaves are folded about a point intermediate the ends of the leaf and the lamina or web of the leaf is stripped from the resulting folds. 95 In the present exemplification of my invention the tobacco leaves, after being untied from the bundle or "hand", are placed on a feed table and while in position on said table the leaves are seized or taken hold of by means of gripping elements fed to the table, the leaves being gripped at a point or portion intermediate the ends of the leaf and the so gripped leaves are fed forward to be stemmed. This exemplification of my invention is shown in the drawings and referring to Figure 1 of the drawings, I show mounted on a bracket 10 forming part of the stationary framework 11 a support 12; and on the said support 115 I provide the inclined feed table 13. Upon the table 13 are placed the individual leaves which are untied from a "hand," the leaves being positioned on the table so as to be capable of being seized by the gripping means active on a point of the stem intermediate the ends thereof. To this end the table 13 is provided with a section or portion 14 lying below the path of the grippers, as will appear presently, and connected to the said section 14 I provide a gauge board 15 functioning to align the butts of the leaves, the said gauge board 15 being adjustably connected to the table section 14 as by means of the slot and wing 120

nut means 16, the adjustability of the gauge board 15 being provided to the end of adapting the machine to various lengths of tobacco leaves. The leaves L are placed on the table with the butts preferably aligned by the gauge board 15, as clearly shown in Figure 1 of the drawings, the intermediate portion of the leaves being located in the space between the table 13 and its 10 extended section 14.

To the end of providing means for gripping the leaves and for feeding them forwardly, I preferably provide a feeding apparatus of the type shown in my prior 15 Patents No. 1,268,392 of June 4, 1918 and 1,286,124 of November 26, 1918, the said feeding means comprising generally endless companion carriers of the sprocket chain type, the said sprocket chains carrying complementary gripping bars for seizing and feeding the leaves through the stemming apparatus. Referring to Figure 1 of the 20 drawings, I show the sets of companion sprocket chains, one set being shown in the drawings and designated as 17 and 18 respectively, the said sprocket chains being trained over opposed sprocket gears 19, 20; 21 and 22 respectively. The sprocket gears 19 to 22 are suitably journalled in bracketed structures 23 and 24 forming part of 25 the stationary framework 11 of the machine, the sprocket gears being positively actuated to be movable in synchronism by any desirable mechanism.

30 Spacedly mounted in the sprocket chains 17 and 18 I provide sets of complementary gripping elements in the form of gripping bars, the said gripping bars being fed into coacting clamping condition for gripping 35 and feeding the tobacco leaves. This is clearly shown in Figure 1 of the drawings, wherein is shown provided a series of spaced carrier bars 25 on the chain 18 and a series of complementary clamping bars 26 on the 40 endless chain 17. As the companion endless chains are rotated by the synchronously operated sprocket gears, the complementary endless gripper bars 25 and 26 are fed into coacting condition, as clearly shown to the 45 left of Figure 1, the gripper bars 25 and 26 gripping therebetween the leaves L at a region intermediate the ends of the leaves, the leaves so gripped being then fed from the feed table 13 forwardly for the stemming 50 operation with both ends of the leaf drooping, as clearly shown in Figure 1 of the drawings.

The leaves after being gripped and fed forward in the manner hereinabove referred to, are then forwarded and the lamina or web of the leaves is stripped from the resulting folds. For the purpose of folding the leaves any suitable means may be provided and I prefer, as shown in the present 55 exemplification of my invention, to fold the

leaves by the act of feeding the same through the stemming elements, the drooping forward end of the leaf facilitating the folding step. Referring again to Figure 1 of the drawings, I show the provision of

70 stemming elements such as the opposed stemming rolls 27 and 28, these stemming rolls being preferably of the type surfaced with card clothing, the stemming rolls 27 and 28 being suitably journalled in the oscillatable arms 29 and 30 respectively.

The arm 29 is suitably journalled in the framework of the machine and the arm 30 is journalled in the bracketed structure 31 forming part of the frame 11 of the machine, such a construction being fully shown in my Patent No. 1,268,392 of June 4, 1918. The arms 29 and 30 may be provided with adjustable tensioning elements as shown in my said patent

80 for the purpose of adjusting the stemming action of the said rolls. The tobacco leaves gripped between a carrier bar 25 and a clamping bar 26 are fed by the endless chains to and between the card clothing rolls 27 and 28, these rolls separating under tension

85 to permit the leaves to pass therebetween, the advance or butt end of the leaf being lapped or folded under the rear end of the leaf by the act of feeding the said leaf between the stemming rolls. The separation of the stemming rolls 27 and 28 and the folding of the leaf therebetween is clearly shown in Figure 3 of the drawings.

90 In the onward movement of the gripping bars 25 and 26 after the latter pass the stemming rolls 27 and 28, the stemming rolls close upon the tobacco leaves as clearly shown in Figure 4 of the drawings, the stripping action of the said stemming rolls

95 commencing at such time. The rolls 27 and 28 are rotated in opposite directions as indicated by the arrows in the figures, suitable means being provided and connected to the other operating parts of the apparatus for imparting the desired rotation to the stemming rolls.

100 With the feeding forward of the bars and the rotation of the stemming rolls 27 and 28, the lamina or web of the leaf L is stripped from the overlying folds of the leaf, the coacting movement between the gripping bars and the rolls effecting a sluffing or wiping stripping action on the leaf web, the relative movement of the parts of the apparatus effecting a simultaneous

105 stripping or detaching of the folds of the leaf from the stem, as clearly indicated in Figure 5 of the drawings.

110 For the purpose of effecting a secure gripping of the bars 25 and 26 as the same are passed between the stripping rolls 27 and 28, I may provide the opposing pressure shoes 32 and 33 acting on complementary

115 bights or reaches of the companion chains 17 and 18, the shoe 32 being preferably stationary mounted on the framework of the

120

125

130

machine and the shoe 33 being yieldingly mounted on the same, the said shoe 33 being resiliently mounted for yielding movement by means of the adjustable spring pressure elements 34 and 35 connecting opposite ends of the shoe 33 to upstanding bearings 36 and 37 respectively, the latter forming part of the framework of the machine.

I have found in the practice of the method 10 carried out by the above described apparatus, that the tobacco leaves may be folded about an intermediate point without breaking or snapping and that the leaf when so folded may be effectively stemmed by the 15 simple stripping apparatus hereinabove described. I have further found that by this method and means the stem may be securely gripped at a relatively tough portion thereof, and that when the leaf is folded 20 about the gripped point and more particularly about the complementary grippers with the lamina simultaneously stripped in the same direction by the opposing stemming rolls, that the tendency for the leaf 25 and the stems to slip between the gripping bars during stripping action is effectively minimized with the resulting increase in stemming efficiency, the simultaneous action 30 of the stripping rolls on the overlapping folds furthermore tending to equalize the pulling strains on the opposite folds, this being another factor in preventing slipping of the stems between the gripper bars. With 35 my method and apparatus, furthermore, the leaves L may be fed to the table 13 without that degree of accuracy hitherto found necessary in prior machines where the alining of the butts involved the need for care and accuracy of feeding of the stems to 40 the gripper elements, the leaves when in fact fed indiscriminately on the table 13 in my invention being properly taken hold of at some intermediate point by the gripping bars 25 and 26. In prior machines where 45 the butts of the leaves are gripped and fed forwardly, the improper positioning of the leaves on the table oftentimes results in a decreased productivity or yield of the apparatus for the reason that such improper 50 feeding results in improper gripping by the bars, this yielding a high percentage of "drops" and also resulting at times in missing the leaves and failing to feed them at all. In the practice of my method, furthermore, 55 it is unnecessary to preliminarily strip the leaf from the butt ends, preliminary butting apparatus being thereby eliminated. Moreover, with the apparatus I provide, the leaves are fed in a simple manner through 60 a set of stemming elements, the law of operation of the machine being relatively simple with the resulting yielding of more consistent and uniform results.

In the feeding of the leaves through the 65 stripping elements 27 and 28 the leaves are

preferably so stripped as to effect complete stemming in a single operation. In my pending application, Serial No. 521,319, filed Dec. 10, 1921, I provide a construction in which the lamina of the leaves is stripped 70 from the folds of the same with a portion of the web or lamina left adhering to the stem adjacent the gripped portion thereof with means provided for subsequently stripping such adhering lamina from the 75 stem. In the present exemplification of my invention I provide a construction in which complete stemming is effected in a single operation while the leaves are moving between the stemming rolls 27 and 28. To 80 this end my present invention comprehends means for moving the stem between the gripper bars while the leaves are being moved between the stemming rolls and to effect this the gripper bars are rotated so 85 that the web adhering to the stem at the gripper bars will be presented to the stemming rolls to be stripped thereby. To accomplish this the lower gripper bar 25, reference being had particularly to Figures 90 2 and 6 to 8, is provided with opposed trunnions 38 rotatable in adjacent links of the chain carrier 18 and on one of the trunnions 38 is provided the gear wheel 39 which is adapted to engage or mesh with a 95 rack bar 40 as the gripper bar 25 is advanced between the stemming rolls 27 and 28. By this means the lower gripper bar is rotated during stemming action and the upper gripper bar 26 is rotated thereby 100 with the movement of the stems therebetween effected in the direction of the arrows shown in Figures 4 and 5 of the drawings. This rotation is timed and speeded so that the lower portion of the leaf remains practically in immovable contact with the surface of the lower stemming roll while the upper portion of the leaf is drawn through the meshes of the upper roll and the stem drawn out. The cleaned stem is thus drawn 105 forward between the gripper bars and is returned to a point between the meshes of the stemming rolls while the bars are receding from the rolls and the rolls are rotating away from the bars. At this 110 moment the gripper bars cease to rotate and the stemming process continues with the result that all the lamina is removed from the stems as shown in Figure 5 of the drawings and there is no need for further 115 cleaning the stems by a secondary set of stemming rolls.

Referring still to Figures 2 and 6 to 8 of the drawings, the parts are so constructed as to effect the rotation of the lower gripper 120 bar for a limited period as hereinbefore referred to, the parts being, furthermore, so constructed as to permit the engagement between the gear wheel 39 and rack 40 without shock and with facility. To this end the 125 130

rack bar 40 is mounted for reciprocating motion in the runway 41 provided in the framework of the machine and means is provided for effecting the reciprocating motion of the rack bar, such means comprising preferably a connecting rod 42 pivotally connected to one end of the rack bar 40, as shown in the figures, the other end of the rod being connected to the crank arm 43 which is fixed to the shaft 44 of the sprocket wheel 22, as particularly shown in Figure 2 of the drawings. With this construction, referring to Figure 2, it will be seen that as the gripper bars are being moved forwardly with the leaves therebetween and as the gear 39 is about to engage the rack 40, the rack 40 is moved in the direction of movement of the gripper bars so that engagement takes place without shock. It will be further evident that as soon as engagement takes place the rack bar 40 is moved in the reverse direction effecting a quick rotation of the lower gripper bar and the upper gripper bar actuated thereby. For the purpose of causing the teeth of the gear 49 to be presented to the teeth of the rack always in the same relation, I preferably provide the fin 45 on the shaft of the gear wheel 39, and cooperating with this fin I provide the track 46 having the incline 47 at the forward end thereof, the incline being provided for the purpose of engaging the fin and turning the gear wheel so that the gear teeth are presented to the rack teeth always in the same relation, this to prevent binding between these parts.

In Figure 9 I show a modification of the gripper bars to permit the stemming rolls to close upon the tobacco leaves immediately the gripper bars pass the same. To this end I provide the rotating gripper bars 25' and 26' arranged out of vertical alinement with the upper gripper bar in advance of the lower gripper bar. Referring to Figure 9 it will be seen that with this construction the stemming rolls 27' and 28' will close nearer the receding bars and take hold of the tobacco earlier. In this case the lower arm need not be pivoted, the upper roll rising to allow the bars to pass. The lower roll is permanently mounted just below the line of travel of the lower bar.

In Figure 10 I show a still further modification of my invention in which the gripper bars 25² and 26² are corrugated to the end that the stems are better gripped and drawn with greater facility during the rotation of the bars.

The practice of my method and the operation of my apparatus will, in the main, be apparent from the above detailed description thereof. The leaves L, after being untied from the bundle or "hand", are placed on the table 13 and table section 14 with the butts of the leaves preferably alined by the

gauge board 15. The leaves positioned in this manner are then gripped at a point intermediate the ends thereof between the gripper bars 25 and 26 with the leaves then fed forward. As the leaves are advanced by the gripper bars the leaves are fed between the stemming rolls 27 and 28, the latter functioning to fold the advance portion of the leaves under the remaining portions of the same. the leaves so folded being then fed through the stripping rolls 27 and 28 for the stemming operation, the stripping rolls being operative simultaneously on opposite folds of the leaf. The lamina is completely stripped from the leaves in a single operation, the rotation of the gripper bars during movement of the leaves through the stemming rolls effecting the presentation of all the lamina to the stemming rolls for complete stripping action.

From above it will be apparent that I have provided an apparatus in which the leaves may be effectively gripped at an intermediate point and efficiently fed for the stripping step, the stripping apparatus being of relatively simple construction and the cooperation of the feeding and stripping means being such as to permit of high speed of operation, efficient stemming, and easy control by an operator.

While I have shown my device in the preferred form, it will be obvious that many changes and modifications may be made in the structure disclosed without departing from the spirit of the invention, defined in the following claims.

I claim:

1. The method of leaf stemming which consists in gripping the leaf stem at a portion intermediate its ends, in folding the leaf and in removing in the same step the lamina or web of the leaf from the folds and from the said gripped portion.

2. The method of leaf stemming which consists in gripping the leaf stem at a point intermediate its ends, in feeding the same through the stemming elements to remove the lamina of the leaf from the gripped point of the stem toward the leaf ends, and in changing the point of gripping while the leaf is fed through the stemming elements.

3. The method of leaf stemming which consists in gripping the leaf stem at a point intermediate its ends, in feeding the same through the stemming elements to remove the lamina of the leaf from the gripped point of the stem toward the leaf ends, and in progressively changing the point of gripping while the leaf is fed through the stemming elements whereby the leaf may be completely stemmed while fed through the stemming elements.

4. The method of leaf stemming which consists in gripping the leaf stem by means of gripping elements at a point intermediate

its ends, in then feeding the gripper elements and the leaf through stemming elements and in moving the same in the gripper elements during feeding of the same through the stemming elements whereby all parts of the web of the leaf are subjected to stripping action.

5. The method of leaf stemming which consists in gripping the leaf stem at a point intermediate its ends, in folding the same and in feeding the folds through stemming elements to remove the lamina of the leaf from the gripped point of the stem toward the leaf ends, and in changing the point of gripping while the leaf is fed through the stemming elements.

6. An apparatus for leaf stemming comprising means for gripping the leaf stem at a point intermediate its ends whereby the leaf may be folded, means for stemming the leaf in folded condition and means for varying the gripping point of the stem during the stemming action.

7. An apparatus for leaf stemming comprising means for gripping the leaf stem at a point intermediate its ends and means for detaching the complete lamina or web of the leaf in a single stemming operation.

8. An apparatus for leaf stemming comprising means for gripping the leaf stem at a point intermediate its ends whereby the leaf may be folded, stemming elements, means for feeding the leaf in folded condition through the stemming elements and means for varying the gripping point during stemming action whereby all parts of the leaf web will be subjected to such action.

9. An apparatus for leaf stemming comprising a movable leaf carrier, movable leaf gripping means in said carrier, stemming means associated therewith and means for moving the gripper means in the carrier when the said gripper means cooperates with the stemming means for stemming the leaf.

45 10. An apparatus for leaf stemming comprising opposed stemming rolls, complemental endless chain carriers, companion gripper bars movably mounted in the carriers, the gripper bars being arranged to cooperate with the stemming rolls for movement between the said rolls during leaf stemming activity and means for moving the bars in the carriers during such activity.

11. In an apparatus for leaf stemming, 55 complemental carriers and companion gripper bars mounted in the carriers, the gripper bars being rotatable in the carriers.

12. In an apparatus for leaf stemming, complemental chain carriers and companion gripper bars mounted in the carriers, the gripper bars being rotatable in the carriers. 60

13. In an apparatus for leaf stemming, complemental carriers and companion corrugated gripper bars mounted in the carriers, the gripper bars being rotatable in the carriers. 65

14. In an apparatus for leaf stemming, complemental carriers and companion gripper bars mounted in the carriers, the gripper bars being rotatable in the carriers and means for rotating the bars in the carriers. 70

15. In an apparatus for leaf stemming, a movable endless chain carrier, a rotatable gripper bar in the carrier, the said gripper bar including gear means, and mechanism operative to rotate the gear means and the bar during movement of the carrier, the said mechanism comprising a rack engaging the gear. 75 80

16. In an apparatus for leaf stemming, a movable endless chain carrier, a rotatable gripper bar in the carrier, the said gripper bar including gear means, and mechanism operative to rotate the gear means and the bar during movement of the carrier, the said mechanism comprising a reciprocating rack engaging the gear. 85

17. An apparatus for stemming leaves, comprising means for gripping the leaf stem at a point intermediate its ends whereby the leaf may be folded and means for stemming the leaf in folded condition, the gripping means comprising a plurality of rotatable gripping bars between which the leaf stem 90 is held, one of the bars being situated in advance of the other.

18. An apparatus for stemming leaves comprising means for gripping the leaf stem at a point intermediate its ends whereby the leaf may be fed in folded condition, a plurality of relatively movable stemming rolls having their axes in a vertical plane and means for feeding the folded leaf through the stemming rolls, the gripping means comprising a plurality of rotatable gripping bars between which the leaf stem is held, one of the bars being situated in advance of the other. 100 105

Signed at Lynchburg, in the county of Campbell and State of Virginia, this 6th day of Dec., A. D. 1921. 110

FREDERICK C. SCHOFIELD.
